UNITED STATES PATENT OFFICE.

HARRY L. HOENIGSBERGER, OF CHICAGO, ILLINOIS.

ROBE.

1,070,892.

Specification of Letters Patent.

Patented Aug. 19, 1913.

Application filed February 7, 1910. Serial No. 542,504.

To all whom it may concern:

Be it known that I, HARRY L. HOENIGSBERGER, a citizen of the United States, and a resident of the city of Chicago, in the county of Cook and State of Illinois, have invented certain new and useful Improvements in Robes; and I do hereby declare that the following is a full, clear, and exact description of the same, reference being had to the accompanying drawings, and to the numbers of reference marked thereon, which form a part of this specification.

This invention relates to improvements in blankets and robes and particularly to the borders of robes.

Most robes heretofore have been constructed with a pinked felt border or other border which in usage has proven unsubstantial. Such borders are extremely weak, easily torn and are not satisfactory owing to the shabby appearance presented after slight use of the robes.

It is an object of this invention to provide a blanket or robe border which is reinforced by suitable means to prevent the edge of the border becoming frayed or torn.

It is further an object of this invention to provide a robe border which is strengthened by the folding of the material forming the border and in which the construction is further strengthened by the insertion of a suitable reinforcement between the layers.

The invention relates to the matters hereinafter described and more fully pointed out and defined in the appended claim.

In the drawings: Figure 1 is a top plan view of a robe embodying this invention. Fig. 2 is a fragmentary transverse section taken through the border showing one method of reinforcement. Fig. 3 is a fragmentary detail of the border showing a cord reinforcement. Fig. 4 is a transverse section showing a plurality of reinforcing cords. Fig. 5 is a fragmentary transverse section taken through the border illustrating another method of reinforcement.

As shown in the drawings: the border 1, comprises a strip or piece of felt or other suitable material which is folded to provide an upper fold 2, and a lower fold 3. The ends of said folds are firmly secured between the margins of the top layer 4, of the robe and the lining layer 5, by sewing or in any other suitable manner. As shown in Fig. 2, a reinforcing cord or other flexible member 6, is secured between the folds 2

and 3, of the border and is held at the outer margin of the border by a line of stitching which also strengthens the margin. Any number of rows of stitching may be provided, dependent upon the width of the border. As shown in Fig. 4, a plurality of reinforcing cords 6, are secured between the upper and lower folds 2—3. Said cords are spaced suitable distances apart and rigidly secured in place by rows of longitudinal stitches. Fig. 5 discloses a reinforcement comprising a strip of canvas 7, or other suitable material which has the outer edge rolled or folded at 8 to provide a longitudinal bead or circular rim. Said reinforcing layer is secured between the upper and lower layers 2—3, and the rounded part secured in the bend formed by folding said layers. The border thus constructed is exceedingly durable. Owing to the cord or cords or layer secured in the margin of the border, the felt or material of which the border is formed can be torn only with great difficulty—in fact, it is necessary to use a knife or other sharp instrument and deliberately cut the border.

All borders heretofore constructed tear readily when accidentally stepped on and pulled or picked with the fingers, or if the border catches in a nail or other projection the nail pulls through the border, giving the same a tattered appearance. With the construction herein described, however, if a nail catches in the border the robe ordinarily cannot be pulled hard enough to break the cord or tear through the tough reinforcing layer and the failure of the border to rend will necessitate releasing the border and thus only a small aperture will be formed. By securing the border between the top and lining, a very rigid construction is formed and one that it is exceedingly difficult to pull loose.

Any suitable material may be used and any number of layers. Also, the reinforcing means may vary through a wide range and may be constructed of any suitable material such as cord, rawhide or other suitable material, or, if preferred, a reinforcing layer of leather, rawhide or other suitable material may be secured between the folds of the border. In fact, any suitable reinforcement may be used between the folds of the border and many other changes may be made without departing from the principles of this invention. I therefore do not pur-

pose limiting myself otherwise than necessitated by the prior art.

I claim as my invention:

A robe, embodying an unfolded top layer, 5 an unfolded lining lying in parallel relation throughout with said top layer, a folded strip of material having both ends thereof engaged between said top layer and lining and extended as to its body portion beyond the edges of said top layer and lining 10 to form a flexible border, and reinforcing

means secured between said folds and embodying an enlargement at the outer edge thereof.

In testimony whereof I have hereunto 15 subscribed my name in the presence of two subscribing witnesses.

HARRY L. HOENIGSBERGER.
